The ornamental design for a tissue marker for intracorporeal site identification, as shown and described.

DESCRIPTION

FIG. 1 is a perspective view of a tissue marker for intracorporeal site identification showing the new design, as viewed from the front upper right;

FIG. 2 is a perspective view of the tissue marker, as viewed from the front lower right;

FIG. 3 is a perspective view of the tissue marker of FIG. 2, rotated clockwise 90 degrees;

FIG. 4 is a perspective view of the tissue marker, as viewed from the rear lower left;

FIG. 5 is a front view of the tissue marker;

FIG. 6 is a right side view of the tissue marker;

FIG. 7 is a left side view of the tissue marker;

FIG. 8 is a top view of the tissue marker; and,

FIG. 9 is a bottom view of the tissue marker.
